TABLE LAMP OR THE LIKE

Albert H. Bien, Philadelphia, Pa.

Application August 26, 1949, Serial No. 4,699

Term of patent 7 years

(Cl. D48—20)

To all whom it may concern:

Be it known that I, Albert H. Bien, a citizen of the United States, residing in Philadelphia, Pennsylvania, have invented a new, original, and ornamental Design for a Table Lamp or the like, of which the following is a specification, reference being had to the accompanying drawing, forming part thereof.

In the drawing:

Fig. 1 is a front elevation of a table lamp or the like, showing my new design;

Fig. 2 is a rear elevation of the same;

Fig. 3 is a top plan of the same;

Fig. 4 is a bottom plan of the same; and

Fig. 5 is a section on line 5—5 of Fig. 1.

The drawing is shaded to indicate contrasting color.

I claim:

The ornamental design for a table lamp or the like, as shown and described.

ALBERT H. BIEN.
